UNITED STATES PATENT OFFICE.

FREDERICK ARCHIBALD, OF VIRGINIA, MINNESOTA.

MUSIC-LEAF TURNER.

1,125,250.

Specification of Letters Patent.

Patented Jan. 19, 1915.

Application filed December 12, 1912. Serial No. 738,304.

To all whom it may concern:

Be it known that I, FREDERICK ARCHIBALD, a citizen of the United States, residing at Virginia, in the county of St. Louis and State of Minnesota, have invented certain new and useful Improvements in Music-Leaf Turners; and I do hereby declare the following to be a full, clear, and exact description of the invention, such as will enable others skilled in the art to which it appertains to make and use the same.

This invention relates to music leaf turners, and it more particularly relates to an improved form of pedal-operated leaf turner.

An object of the invention is to provide a device of this character which may be employed on pianos and organs of various kinds, and adjustably fitted thereto.

Another object of the invention is to provide improved means, whereby the music leaves may be turned alternately back and forth by mechanism connected with a suitable pedal.

Another object of the invention is to provide for turning any number of leaves from one to four, and then turning the leaves back into their normal positions.

Another object of the invention is to provide a device of this character which is comparatively simple of construction, compact, economical, and thoroughly efficient in operation.

Other objects and advantages may be recited hereinafter and in the claims.

In the accompanying drawings, which supplement this specification, Figure 1 is a front elevation view of my improved leaf turner supporting a piece of music. Fig. 2 is a rear elevation view, illustrating the operating mechanism. Fig. 3 is a fragmental sectional view taken on the line 3—3 of Fig. 2. Fig. 4 is a detail view, in perspective, of one of the jointed levers. Fig. 5 is a vertical sectional view through one of the jointed levers and its adjuncts. Fig. 6 is a fragmental perspective view of the vertical slide beam or carriage and certain of its adjuncts, and, Fig. 7 is a fragmental detail view of the double-acting catch or slide-bar-engaging element.

Referring to these drawings, in which similar reference characters designate corresponding parts throughout the several views, the base or frame 10 is formed from a plate of metal or other suitable material.

This plate 10 is provided with apertures 11 through which the curved ends of a supporting bracket 12 extend, the lower portion of said bracket being covered with felt, rubber or other soft and pliable material, so that the piano or organ will not be scratched or marred thereby when in operative position, as shown in Fig. 3.

A fender 14 is secured on the bracket 12, said fender being covered with the same kind of material as that which constitutes the element 13.

Buttons 15 are pivoted at 16, to the base plate 10, said buttons being provided with lever arms 17 by which the buttons may be alternately turned into and out of engagement with the bracket 12, so that the same may be removed from one pair of holes and placed in another pair, for adjusting the position of the bracket with relation to the base plate.

Formed at the upper end of the plate 10, and preferably struck up therefrom, are oppositely disposed pairs of apertured lugs 18, and through the apertures of these lugs extend the parallel end portions of a rest bracket 19, the intermediate and top portions of said bracket being covered with felt or the like, as at 20, thumb screws 21 being provided, in contact with the bracket 19, for retaining the latter in adjusted position.

At the bottom of the plate 10 is a vertical slot 22 through which extends the lower forward extension 23, of the vertical slide bar 24, or carriage 24, and upon this carriage is pivotally mounted a shifter beam 25, the pivotal point thereof being indicated at 26.

Pivoted at 27, on the end of the beam 25 is a shifter plate 28 having an arcuate slot 29 therein, for receiving a headed stud 30 which extends rearwardly from the beam 25.

On a laterally extending arm or plate 31 is secured a coiled spring 32, connecting with a link 33 which is pivotally connected at 34 with the plate 28; the function of the spring 32 being to retain the plate 28 in either of its alternative positions, in which the stud 30 will rest alternately in the respective ends of the slot 29 owing to the fact that the pivot point 34 will be thrown to either side of the vertical axis of the pivot point 27. The carriage 24 is held normally in its uppermost position, as shown, by means of a spring element 35, secured to the plate at 36 and loosely connected to the carriage by means of the stud 37. The lug 23 is

apertured for the reception of a thin strip 38, of steel or other suitable metal, which extends downward between the keys of the piano and through a suitable aperture there- 5 beneath (not shown), whence it may connect with any suitable form of pedal, whereby it may be drawn downward, so as to draw the carriage 24 downward, together with the bar 25 and plate 28 and their adjuncts.

10 Secured on the base plate 10, approximately centrally thereof, is a guide member 39 provided with a central slot through which extends the reduced upper end 24' of the carriage 24, said end 24' and the forward extension 23 serving to guide the carriage in its vertical reciprocations.

15 Adjacent to the upper end of the beam 25 is a rearwardly extending stud 40, and at the end of said beam 25 is pivoted the double-toothed catch 41, which is adapted to freely oscillate laterally of the beam 25.

20 At opposite sides of the extension 24' is a series of guide apertures formed in the guide members 39, and within these guide 25 apertures are slidably seated pairs of slide bars 42, each pair of slide bars being connected to the opposite ends of a lever or bell crank, through the medium of links 43. The bell cranks 44 and 45 are pivoted at 46 30 and 47, respectively, to the base plate 10. Each slide bar 42 is provided with rearward extensions 42' and 42'', the latter being adapted for engagement by the catch 41. The lower ends of the slide bars 42 extend 35 under a guide plate 39', which constitutes a part of the guide member 39.

25 The upper middle portion of the base plate 10 is provided with an aperture 48 in which is seated a number of plates or tables 49, said tables extending laterally beyond the aperture 48, and being fixedly secured to the base plate by means of vertical securing bars 50. The plates 49 are equally spaced apart, and provided with fixed studs 45 51 over which work a series of jointed levers, each consisting of a lever member 52 and a second lever member 53, the lever members being pivoted together by means of pivots 54. One end of the member 52 is slotted, at 50 52' for receiving the fixed stud 51. Loosely connected to the rearwardly extending end of each member 53 is one end of a link 55, the other end thereof being loosely connected, at 56, to one of the bell crank levers 54 or 45; it being understood that there is a link 55 for each jointed lever and for each bell crank lever. A vertical pivot pin 57 extends through all of the tables or plates 49 and through all of the lever members 53, 55 so that all of the jointed levers are pivoted concentric with relation to each other, and their concentric axes are in fixed position relative to the base plate 10.

60 Each member 52 is provided with a longitudinal bore 52', a longitudinal slot 52''

communicating with the bore, and a recess 52'' extending downwardly from the bore.

65 Seated in the bore 52' of each member 52 is one end of a leaf-engaging arm 58 having a downwardly extending tongue 59 fitted in the recess 52''.

70 Each arm 58 is provided with a shoulder or spring seat 60, a sleeve 61 being seated against the member 52 and being slidably seated on the arm 58. A spring 62 surrounds each arm 58, between the shoulder 60 and sleeve 61; so that, by moving the arm 58 longitudinally in the direction of the member 52, the tongue 59 is moved out of engagement with the recess 52'', and may be 75 turned into the slot 52'', so that it may be drawn through the slot, for allowing the arm 58 to be disconnected from the member 52.

75 Each arm 58, except the lower arm, is bent downward and thence extended laterally, so that all of the arms 58 terminate or substantially the same horizontal plane, and on the end of each arm 58 is secured a suitable spring-actuated leaf-clamp 63, which 80 may be of any suitable form and construction for securely holding the top portion of a music leaf, and therefore, there being a multiplicity of these clamps 63, a multiplicity of leaves may be turned separately and 85 in succession. A member 63' is pivoted at 63'' to the clamp 63 and is adapted to bind against the face of the music sheet.

90 The guide member 39 is provided with slots 64 and intervening tongue 65, said 100 slots and tongues being radially disposed with relation to the pivot 27; and it will be seen, that, when the carriage 24 is reciprocated, the stud 40 travels alternately up and down within the slots 64.

95 Pivoted to the base plate at 66 is a jointed

and spring-actuated shifter lever consisting

of a depending element 67 and an upwardly

projecting stop element 68 having a cam

surface 68' thereon, said stop element be-

ing pivoted at 69 to a lateral extension of

the element 67, and a compression spring

70 coacts with a lug 71 for retaining the

element 68 in its normal position relative to

the element 67. The lower edge portion of

the base plate 10 is provided with an arcu-

ate slot 72, having a series of recesses 73

communicating therewith, and a series of

tongues 74 separating these recesses. The

lower end of the member 67 extends for-

wardly through the slot 72, and thence up-

wardly, and is provided with a pair of

parallel lugs 67', between which is pivoted

a latch 75 having its pivot 76 adjacent to its

upper end, and having a stud 77 extending

rearwardly into one of the recesses 73, a

spring 78 being provided on the member

67, in contact with the member 75, for re-

taining it in its normal closed position, as

shown in Fig. 3. The lower end of the

130

member 67 constitutes a handle by which the stud 77 may be disengaged from the recess 73, so that the member 67 may be swung longitudinally of the slot 72, and thereby 5 change the adjusted position of the stop member 68'. Adjacent to the lower corner of the shifting plate 28 is a forwardly extending stud 79, adapted to impinge upon the top of the member 68, for shifting the 10 plate 28 from the position shown, to its other alternative position, in which the stud 30 will rest in the opposite end of the arcuate slot 29, and the stud 34 will then be on the opposite side of the carriage 24 from 15 its present position.

A setting lever 80 is pivoted at 81 to the base plate 10, and is provided with a stud 82, adapted to impinge upon the edge 28' of the plate 28, when the lower arm of the 20 lever 80 is swung laterally. In order to swing the lever 80, a pull rod 83 is pivotally connected at 84 to the upper arm of the lever 80, and the rod 83 is extended downward and terminates in a forwardly extending 25 finger piece or handle 83', which extends through a slot 85, in the base plate. The lever 80 is pivotally connected at 86 with a spring 87, secured to the guide member 39, and by means of this spring, the lever 80 30 and pull rod 83 are returned to their normal positions, as shown; the rod 83 acting as a stop for the stud 82.

In operation, the operator pulls the carriage 24 downward, by means of the strip 38, as described, thereby drawing the catch 41 downward; and, said catch being in engagement with the arm 42^a of the left-hand bar 42 (see Fig. 2), this bar 42 is pulled 40 downward so as to swing the bell crank 44 to which it is connected by one of the links 43, so that the other link 43, which is attached to the opposite arm of this bell crank and to the adjacent slide bar 42, draws this adjacent slide bar upward while 45 the beam 25 goes downward, until the arm 42^a of the upwardly moving slide bar is on a higher plane than the upper end of the beam 25, and the stud 40 clears the lower end of the adjacent tongue 65, so that the beam 25 50 is drawn laterally, by means of the plate 28, link 33 and spring 32; so that the stud 40 now registers with the next succeeding slot 64, the movement of the beam 25 having been arrested in this position by means of 55 the arm 42^a of the contiguous bar 42 upon which it has impinged. Now, as the bell crank 44 was swung on its pivot, by the operation just described, the upper link 55 caused the upper jointed lever to swing on 60 its pivot 57, thereby swinging the arm 58, together with its clamp 63 and the music leaf clamped thereby, through an angle of one hundred and eighty degrees. It will be noted that the member 53 is swung through 65 a considerably less angle than one hundred

and eighty degrees, but the swing of the member 52 and arm 58 is increased by means of the leverage gained by the pivotal connection at 54 and the stud and slot connection at 51 and 52^a (see Fig. 4). Referring 70 to the preceding operations, wherein the stud 40 is in registry with the second slot, it will be seen that upon allowing the carriage 24 to ascend, the stud 40 will move up into this second slot, and the catch 41 will engage with the arm 42^a of the third slide bar 42; so that when the carriage 24 and its adjuncts are again lowered, this third bar 42 will be engaged by the catch 41, so as to rock the bell crank 45 to which it is connected; thereby actuating the second jointed lever and turning the second music leaf, in the same manner that the first music leaf was turned. This operation continues until all of the slots 64 have been entered by the 80 stud 40 and until all of the leaves have been turned, in which operation all of the bars 42 have been moved and all of the bell cranks have been swung on their pivots; provided that there are just four music 90 leaves to be turned. It will be seen that as the upper end of the beam 25 swings rightward (see Fig. 2), its lower end swings leftward, thereby drawing the lower end of the plate 28 and its stud 79 leftward; so that, 95 at this stage, when the carriage 24 is again drawn downward, the stud 79 will be arrested by the upper end of the stop 68, and the plate 28 is thereby swung leftward on its pivot 27 until the stud 30 rests in the 100 right-hand end of the slot 29. In swinging leftward, the plate 28 carries the rod 33 leftward beyond the pivot 27, so that the upper end of the beam 25 tends to move leftward, so that when the stud 40 is released from the right-hand slot 64, it moves into registry with the second slot 64 to the left, and is there arrested by the bar 42 immediately to the left thereof, having impinged upon the arm 42^a of said bar. During 110 this rightward movement, the beam 25 and its adjuncts have pulled each alternate slide bar 42 downward, and thereby caused the other alternate slide bars to move upward, and now, in this return movement of the beam 25 and its adjuncts, the bars that were formerly moved upward are now pulled downward, so that the bell-cranks 44 and 45 are moved in the opposite direction, so as to swing the jointed levers, the 120 arms 38 and the music sheets in the opposite direction; so that by several rapid oscillations of the carriage 24 the leaves are quickly returned to their normal position, in case it is desired to play the music over 125 again.

In order that the music may be properly supported, I provide a shelf 88, preferably composed of two similar halves, which are provided with apertured ears 89, and 130

through the apertures of these ears extends a vertical rod or supporting bracket 90, having teeth 90' with which one or more of the ears 89 engage, for retaining the shelf 88 in adjusted position, so that the music may be raised or lowered, to suit the requirement. The rod 90 may be secured on the plate by any proper means, but it is preferably removably secured, and this may be accomplished by suitably bending the lower end thereof and inserting it through an aperture 91 in the plate 10, and securing its upper end by means of a hook 92.

In order that the music may be held firmly in place on the shelf 88, I provide a pair of spring clamps 93, pivoted to the plate at 94 and adapted to be swung down into engagement with the outside leaves of the piece of music, so as to clamp it against the base 10.

When it is desired to turn only three sheets of music, the stud 77 is engaged with the third notch or recess 73 instead of the fourth, and so when it is desired to turn only two sheets of music and return them to their normal positions, said stud 77 is engaged with the second recess 73; but when it is desired to turn one leaf back and forward a number of times, the stud 77 remains in its normal position.

While I have described a device which is designed for turning the maximum of four music leaves, it will be understood that I do not limit my invention to this specific construction; and neither do I limit my invention to the exact details of construction, combination and arrangement of parts, as herewith described and illustrated, but my invention may only be limited by a reasonable interpretation of the claims.

Having shown and described a device which is fully capable of attaining the foregoing objects, in a thoroughly practical and efficient manner; I claim:—

1. In a music leaf turner, a base plate adapted to be seated on a piano and having means thereon for supporting music leaves, a series of leaf-engaging elements mounted on a substantially vertical axis, a series of elements pivoted on a vertical axis and adapted to be swung through an arc of less than one hundred and eighty degrees and operating on the leaf-engaging elements for swinging them through one hundred and eighty degrees, a link connected with each said member, a bell crank connected with each said link and pivoted on a horizontal axis, a slide bar connected with each said bell crank, a catch for successively engaging and moving the respective slide bars, and means for actuating the catch.

2. In a music leaf turner, a base plate adapted to be seated upon a piano, means on the base plate for supporting music leaves, a series of jointed levers mounted for rota-

tion on a vertical axis and each carrying a leaf-engaging member, a series of pairs of slide bars, a bell crank pivoted on a horizontal axis connected with each pair of slide bars and with each jointed lever, a catch, means for actuating the catch for moving it alternately into engagement with one of the slide bars of each pair, and means for shifting certain operating mechanism of the catch-actuating means for causing the catch to successively engage and move the other slide bars of each pair, substantially as described.

3. In a music leaf turner, a base having means thereon for supporting music leaves, mechanism on the base in engagement with the leaves for turning the same, said mechanism comprising a series of levers and links and slide bar operatively connected, a carriage mounted for reciprocation, a shifter beam pivoted on the carriage and having a catch adapted for engagement with the slide bars, a shifter plate pivoted on the shifter beam and having a spring connected therewith for actuating the shifter plate and shifter beam in either of two alternate directions, means for automatically shifting the shifter plate when the carriage is reciprocated, and means for returning the shifter plate into its normal position.

4. A music leaf turner comprising a base, a plurality of parallel spaced and horizontally disposed plates projecting therefrom, a plurality of pivoted levers playing upon said plates, a plurality of arms operated by said levers to turn the pages of music sheets, a plurality of pivoted bell-crank levers connected to said first mentioned levers by means of links, a plurality of approximately vertically sliding members connected to said bell-crank members by means of links, said last mentioned means being connected in pairs to said bell-crank levers, on the opposite sides to said pivoted points of the levers so that when one of said vertically operating means is drawn downwardly the opposite means will be raised upwardly, means to draw downwardly one of said vertically operating means, automatic means to shift said drawing means to actuate a second vertically operating means after the first said vertically operating means has been drawn downwardly, and means to restore said drawing means to its original position.

5. A music leaf turner comprising a plurality of pivoted arms actuating to turn the pages of music leaves, a plurality of operating means, a plurality of multi-part connecting means connecting each of said operating means to each of said arms, means to actuate each of said operating means successively, means to guide said actuating means from one of said operating means to the next operating means in successive

order, means to reverse said actuating means, means to restore the music sheets successively to their first position, said last mentioned means consisting of a pivoted member having an arcuate slot therein, means connected to said actuating means and playing in said slot to be operated by said pivoted means, means to hold said pivoted member into operative position, means of automatically reversing said pivoted

member and means to reverse said actuating means when said pivoted member is reversed.

In testimony whereof I have signed my name to this specification in the presence of 15 two subscribing witnesses.

FREDERICK ARCHIBALD.
